VENDING MACHINE

Carl V. Tardete, Jamestown, N. Y.

Application September 7, 1937, Serial No. 162,805

5 Claims. (Cl. 312—78)

This invention relates to a vending machine and particularly aims to provide a novel construction to simultaneously vend an article or commodity with an accessory, particularly a cigarette or cigar and a match, although the invention is not so limited because it may be used with or without the vending of the accessory.

It is an object to provide such a machine having a novel vending mechanism to dispense one article at a time, and a novel coin-controlled operating means for the vending mechanism.

The more specific objects and advantages will in part be pointed out hereinafter and otherwise become apparent from a consideration of the following specification taken in connection with the accompanying drawings, illustrating one operative embodiment by way of example.

In said drawings:

Figure 1 is a view of the improved vending machine in perspective and partly broken away;

Figure 2 is a front elevation, partly in vertical section, to disclose details;

Figure 3 is a perspective view of the outer front panel;

Figure 4 is a perspective view of the operating knob for the main or operating shaft;

Figure 5 is a vertical sectional view through the machine taken at a right angle to Figure 2;

Figure 6 is a perspective view of the front wall of the cabinet and parts mounted thereby;

Figure 7 is a detail perspective view of the ejector device;

Figure 8 is a cross section taken on the plane of line 8—8 of Figure 6;

Figure 9 is a detail fragmentary perspective view of a modified form;

Figure 10 is a detail perspective of a second modified form, and

Figure 11 is a perspective view of an electric lighter which may be employed for the dispensed cigarettes or cigars.

Referring specifically to the drawings wherein like reference characters designate like or corresponding parts in the different views, and first to Figures 1 to 8, a suitable cabinet is provided at 10 having a hopper 11 at the top thereof which is adapted to contain the cigarettes, cigars or other articles or commodities to be dispensed, the same being shown at 12 and disposed in parallelism. Said cabinet includes a base wall 13, rear wall 14, side walls 15 and a front wall 16, held together in any suitable way and preferably by angle strips 17 and screws or other fastenings 18.

Said hopper 11 may be of any desired construction having walls or panels disposed in con-

tinuation of the front, side and rear walls of the cabinet as at 19, secured in place by bars 20 and 21 at the bottom and top, respectively, and by angle strips 22 and screws or other fastenings 23. Said hopper walls or panels are designated 19 and may be made of any suitable material, for instance metal or glass, or be composite, and they may be finished or ornamented in any suitable manner. Said hopper has a displacement closure 24 at the top thereof adapted to be locked in place at 25, which covers the opening through which the articles 12 are supplied from time to time.

At the bottom of the hopper 11, is a forwardly and downwardly inclined wall which guides the article 12 toward vending position. Behind the front bar 20, a channel member or chute 26 is fastened, the same being generally rectangular and closed except at the bottom and at an opening or slot 27 in the front wall thereof through which the articles 12, one at a time, are vended or discharged, such article rolling or depositing in a trough 28 extending forwardly from and integral with the front wall 16 at the top thereof. A hood 29 is carried by the channel member or chute complementally to the trough 28.

The bottom wall 30 of the hopper terminates short of the wall 16 in a depending flange 31 between which and wall 16, an ejector 32 is guided for sliding movement into and out of the channel member or chute 26. A governor blade 33 is rigid with a rod 34 pivotally disposed transversely on the rear wall of the channel member or chute 26, journaled in the walls 15 and provided with a depending arm 35. A shield 36 is carried by the hopper 11 to prevent undue crowding of the articles 12 against the governor blade 33. Such governor blade 33 has its lower edge so arranged and proportioned with respect to the forwardly inclined bottom wall 30 that normally the space therebetween is insufficient for an article 12 to pass. The aforesaid arm 35, in a manner hereinafter specifically described is adapted to be rocked through the movement of the ejector 32 to swing the arm 33 rearwardly and only sufficiently to provide a sufficient space or pass for a single article 12 to roll forwardly to the position of Figure 5 into contact with wall 16, on top of the ejector 32 and in line with the channel member or chute 26.

Said ejector 32 is detailed in Figure 7. It may consist of a plate 37 having its upper edge portion flanged or returned to provide a forwardly inclined rest 38 in line with the wall 30 on which an article 12 rests at the initiation of a vending

operation. A rack bar 39 depends from the plate 37 and is guided in a U-shaped bracket 40 suitably fastened within the cabinet. A retractile coil spring 41 is fastened to pins 43 and 42 respectively carried by the rack bar 39 and bracket 40 to urge the ejector to lowermost or retracted position.

A horizontally disposed operating shaft 44 is suitably journalled in the front wall 16, having an external head 45 keyed thereon to which is screwed or otherwise fastened at 46, an operating knob 47. A segmental gear 48 is keyed to operating shaft 44 and enmeshed with the teeth of rack bar 39 so that the ejector 32 may be raised for a vending or ejecting operation.

Behind the circular head or disk 45, integral therewith or otherwise rigid with the same and operating shaft, is a control disk or plate 49, forming part of coin-controlling means. In the retracted or normal position of the parts as shown in the drawings, a projection 50 on disk 49 abuts a stop pin 56. A coin or token is adapted to be deposited through a slot 57 in an outer front panel 58, detailed in Figure 3, and removably fastened at 59 to wall 16, and preferably overlapped by adjacent angle members 17. Panel 58 has an opening 60 in which the head 45 is journalled and it also has an inwardly extending coin guide or deflector 61. A coin deposited through slot 57 falls into the space between plate 16 and panel 58 onto the disk 49, partly behind the head 45 and in front of projection 50.

In the said position, the deposited coin abuts an arm 61' of a detent 62 having a vertical shaft 63 (Figs. 6 and 8) journalled in brackets 64 or the equivalent on plate 16. Said shaft also carries an arm 65 and the arms 61' and 65 are rigid with shaft 63 and arm 65 has an extension 65' whereby detent 62 is urged by a leaf spring structure 66 fastened to wall or plate 16 into detaining position through slots 67 and 68, respectively, of wall or plate 16. Arm 65 in its normal or detaining position is disposed in a slot 69 in the periphery of control disk 49 so that the shaft 63 cannot be sufficiently turned to vend an article in the absence of the deposit of a coin into slot 57. When a coin C is deposited, it will bridge the space between the projection 50 and the detent arm 61', so that rotation of the operating shaft 44 will displace the arm 61', rocking the detent shaft 63, withdrawing the detent arm 65 from the slot 69, thus permitting rotation of the operating shaft and parts until a projection 70 on said plate or disk 49 engages an abutment or pin 71 on plate 16, which movement effects a vending operation. The parts being released after the vending operation, return automatically to retracted or normal position under the urgency of spring 41 and spring device 66, the edge portion 72 of plate or disk 49 preventing return of the arm 65 to normal position until the slot 69 returns into registry with arm 65.

The coins fall into the cabinet, guided by the deflector 61 and are removable from time to time through a conventional, key-controlled closure means as suggested at 69'.

Said ejector 32 has a projection 73 engageable with the arm 35 as the ejector is raised in order to move the governor plate or valve 33 rearwardly to permit an article 12 to roll under it to assume the position shown in Figure 5 when the ejector descends or retracts and thus be in position for vending on the next operation of the machine.

Simultaneously with the vending of the cigarette, cigar, or other article 12, an accessory, for

instance a match 74, is discharged through the movement of the ejector 32 and from a hopper or equivalent means 75 located at any desired wall of the cabinet 10, the ejector being shaped 5 according to the position of mounting of such hopper 75. In Figures 1 to 7, such hopper is carried by one of the side walls 15 and an angle arm 76 is provided on the plate 37 of the ejector, as shown in Figure 7, which carries an ejector head 77. Angle arm 76 is vertically movable in 10 a slot in the adjacent side wall 15 so that the ejector head 78 may move vertically in the match hopper 75. Normally the upper surface of head 78 is aligned with the bottom wall 79 of hopper 75 and since both are at the same inclination, upward movement of the head 78 carries a match 74 into line with a discharge slot 80 in the front wall of the hopper, into which the match rolls and is caught in a trough 81 on such hopper. Said hopper 75 may be filled at the top where a displaceable closure 82 is located and which may be under lock and key if desired.

Briefly the operation of the machine is as follows: A coin of predetermined size is deposited 25 in the slot 57 and it travels into contact with the upper edge of plate 49 between projection 50 and arm 61'. Thereupon, knob 47 is turned clockwise and correspondingly turns operating shaft 44, during which movement, said coin displaces the arm 61' which rocks shaft 63 and arm 65 thereon, which withdraws the latter from slot 69 of the control plate or disk 49, movement of the shaft 44 and control plate 49 being limited by engagement of projection 70 on the latter with the abutment pin 71. During such partial rotation of the shaft 44, the segmental gear 48 thereon through its coaction with the rack bar 39 raises the ejector 32, thus ejecting the article 12 engaged on the rest 38 thereof, through slot 30 27 of the channel member 26, onto trough 28 for removal. As the ejector 32 ascends, arm 35 moves inwardly at its lower edge through contact of arm 73 on the ejector, swinging the blade 33 inwardly just enough to enable another article 40 12 to roll under it and into contact with the ejector plate 37, remaining there until the spring 41 returns the ejector to lowered or retracted position, whereupon it rolls onto the rest 38 so as to be vended on the next vending operation of the machine. As the article 12 rolls onto the rest 38, arm 73 disengages arm 35 and blade 33 quickly moves to normal or vertical position to thus prevent the discharge of more than one article 12 at a time. The same movement of said ejector 32 which vends an article 12, also discharges a match 74 since the ejector head 77 on arm 76 moves upwardly through hopper 75 and is of such width as to elevate one match 74 only which falls therefrom through a slot 80 onto a trough 81 for removal.

It is to be understood that various changes may be resorted to within the spirit and scope of the invention. For instance, the modified form of Figure 9 may be employed. Here, the cabinet is designated 82, having a hopper 83, with a channel member 84 at the front thereof, beneath which the articles 12' roll, one at a time, on bottom wall 30' controlled by a blade such as 33 and associated mechanism as in the first form. Such articles fall into a tray or trough 85 of a roller 86 pivoted by means of trunnions 87 in walls of the cabinet. The roller 86 is normally in the position of Figure 9 resting on the upper surfaces of rods 87a carried by a bar 88 at the top of a rack bar 39' similar to that at 39. Otherwise the structure

is the same as that of the preceding figures or as modified in Figure 10. As the ejector raises in this form of Figure 9 following coin operation as hereinbefore set forth, rods 87 swing the roller so as to move trough 85 forwardly, which ejects the article 12' into a trough (not shown) like that at 28, the wide surface of the roller preventing another article 12' from rolling into engagement with the trough 85 until it returns by gravity to retracted position, following retraction of the ejector.

Another modification is suggested in Figure 10. The ejector mechanism for the article and its accessory are modified so that the article will be ejected into a trough 89 and the accessory will be ejected into a trough 90. Said troughs 89 and 90 are inset within the cabinet here designated 10'' and through a side wall at openings 91 and 92, they communicate with trays or supports 93 and 94, respectively. Each trough 89 and 90 has a slot 95 and 96 through its wall, in which an ejecting lever 97 is movable. Such lever 97 is pivoted at 98 to the cabinet 10'' and is engageable by a vertically movable arm 99 of a slide rod 100, loosely disposed in a tube 101 on the cabinet 10''. A suitable part of the operating means carries a projection or cam 102 which engages the said arm 99. Thus, when the operating means is turned following deposit of a coin, cam 102 raises arm 99 and rod 100, the arm swinging lever 97 in the slots 95 and 96 and partially ejecting or extending the article and accessory into the troughs or supports 93 and 94. It will be understood that the machine of Figure 10, except as specifically described, is constructed as in the form of Figures 1 to 7 or Figure 9.

In any form of the invention, a suitable counter may be employed. One is suggested at 103 in Figure 5 which is conventional and operable by an arm or crank 104 on the operating shaft 44. 40

Also, any form of the invention may dispense with the feature of vending a match or other accessory in which event, an electric igniter 105 as in Figure 11 of conventional form, may be separably connected in any desired circuit, and supported on the cabinet of the machine or adjacent thereto, as preferred.

I claim as my invention:

1. In a vending machine, a hopper having an inclined discharge wall, a channel member at the front of the hopper spaced above said wall so that articles may discharge beneath the channel member, an ejector having its upper edge disposed to receive an article from the discharge wall to be ejected, said channel member having a discharge opening, and means operable to raise the ejector so that the article will register with the opening and discharge therethrough.
2. In a vending machine according to claim 1, a blade pivoted on said channel member to normally prevent discharge of articles beneath the latter, and means operable by the ejector to move said blade to periodically enable an article to pass the same.
3. In a vending machine according to claim 1, a blade pivoted adjacent the base of the channel member and having a depending arm, the inclined discharge wall having a depending flange at its forward end behind which the ejector operates, the upper edge of the ejector being inclined similarly to said wall, a projection on the ejector co-acting with said depending arm to operate the blade, and retractile spring means for the ejector.
4. In a vending machine, a front wall, a channel member open at its bottom and having a discharge opening above said bottom, means to support the channel member above the front wall, an inclined wall to feed articles to be vended, an ejector operable behind said front wall to receive the articles from the inclined wall and raise the articles through the channel member into position to discharge through said opening, an operating shaft for the ejector extending through said wall, a head on said shaft, and an exterior panel secured to said wall having an opening in which said head is journaled.
5. In a vending machine according to claim 4, an exterior trough on said front wall at the base of the first mentioned opening, and an exterior hood on the channel member above the first mentioned opening disposed over the trough.

CARL V. TARDETE.
